UNITED STATES PATENT OFFICE

IRVING R. ROWE, OF STONINGTON, CONNECTICUT, ASSIGNOR TO THE ATWOOD MACHINE COMPANY, OF STONINGTON, CONNECTICUT, A CORPORATION OF NEW JERSEY

WINDING MACHINE

Application filed April 25, 1931. Serial No. 532,777.

My invention consists in a double deck winding machine in which there is provided means for preventing the loose end of a broken thread on the winding spool for one deck being thrown over and becoming wound onto the winding spool for the other deck.

My invention more particularly comprises a series of thread guards, as for instance guard plates located between the inner and outer rows of winding spools for the two decks, said guard plates being carried by the bearing brackets for the winding spools; a guard plate being located between each pair of inner and outer spools and their pair of bearing brackets.

A practical embodiment of my invention is represented in the accompanying drawing in which:

Fig. 1 represents a detail top plan view of a double deck winding machine showing one of the double spool winding units with my spool separating guard plate in position therein.

Fig. 2 represents a vertical cross section taken in the plane of the line II-II of Fig. 1.

The usual pair of upper and lower longitudinal side bars 1 and 2 of the winding machine frame have brackets 3 secured at intervals thereto for rotatably supporting the shaft 4 for the friction winding wheels 5.

These longitudinal side bars also have brackets 6 secured thereto at the proper distances apart for receiving between each two brackets a pair of inner and outer winding spools 7 and 8, the rows of inner and outer winding spools in the present instance being designed to wind respectively the threads from the upper and lower decks of swifts (not shown).

The ends of the inner and outer spindles 9 and 10 of each pair of inner and outer winding spools are rotatably mounted in bearings 11 and 12 respectively, in the inner and outer arms 13 and 14 of levers rotatably adjustable on arms 15 uprising from the bracket 6 so that the heads 16 and 17 of said spindles will properly rest upon their friction winding wheel 5. In the present instance each lever 50 is pivoted at 18 to the uprising bracket arm

15 and a clamp bolt 19 passes through the lever and a concentric elongated slot 20 in the arm 15 and is provided with a nut 21 for securing the lever in its proper rotative adjustment.

The means which I have provided for separating the inner and outer winding spools of each pair is shown as a guard plate 22 secured at each side thereof at its lower edge to one of a pair of oppositely projecting lateral ears 23 on the bracket 6. This guard plate projects upwardly and forwardly over the outer spool 8 and effectually separates the two spools and thus prevents the loose end of a broken thread from being thrown over from one spool into a position where it would be wound onto the other spool. This guard plate is shown as having a recess 24 for the free passage therethrough of the periphery of the friction winding wheel 5, thus enabling the lower edge of the guard plate to be brought well down between the inner and outer winding spools.

The bracket 6 is shown as supporting at its outer end the traverse bar 25 and as supporting on an uprising arm 26 at its inner end the traverse bar 27 for the upper deck or inner winding spools.

It is evident that various changes may be resorted to in the construction, form and arrangement of the several parts without departing from the spirit and scope of my invention, and hence I do not intend to be limited to the particular embodiment herein shown and described, but

What I claim is:

1. In a winding machine, inner and outer winding spools, brackets forming bearing supports for the spools, each of said brackets having oppositely projecting ears, and a thread guard plate located between the inner and outer winding spools and secured to its adjacent ears.

2. In a winding machine, a friction winding wheel, inner and outer horizontally disposed winding spools driven thereby, a pair of brackets forming bearing supports for the spools, and an upwardly and forwardly projecting guard plate located between the inner and outer winding spools and their pair

of supporting brackets, said guard plate being secured at each side thereof at its lower edge to its adjacent bracket.

3. In a winding machine, a friction winding wheel, inner and outer horizontally disposed winding spools driven thereby, a pair of brackets forming bearing supports for the spools, and an upwardly and forwardly projecting guard plate located between the inner and outer winding spools and their pair of supporting brackets, said guard plate being secured at each side thereof at its lower edge to its adjacent bracket, the guard plate having a recess for the free passage therethrough of the periphery of the said winding wheel, to permit the guard plate to be located well down between the inner and outer winding spools.

In testimony, that I claim the foregoing as my invention, I have signed my name this 22nd day of April, 1931.

IRVING R. ROWE.
